PRESSING MACHINE

Hans J. Behncke, Putzbrunn, Munich, Germany, assignor
to Equipment Imports, Inc., a corporation of Michigan

Filed Feb. 21, 1962, Ser. No. 174,772

6 Claims. (Cl. 38—66)

This invention relates to improvements in pressing machines as used in the pressing of fabric articles, for example, wearing apparel. In particular, it has reference to a press wherein the articles are pressed while moistened, as by live steam passed through the buck or bed upon which the article rests, or by hand sponging.

In those machines which include a lower buck to receive the article and a movable, heated, upper buck adapted to be moved into pressure contact with the work it has been known to draw off the water and/or vapor by vacuum applied through the lower buck, this latter having a perforate upper surface for that purpose. However, those known to me are inefficient in that the suction is not applied over a sufficiently extended area of the buck or with adequate intensity whereby carrying off of the vapor has been inordinately slow or insufficient. Accordingly, an acceptably pressed article cannot be assured.

The within invention has for its principal object an improved construction for the buck, ordinarily the lower buck, through which vacuum is applied, whereby the entire surface of the buck receives a substantially uniformly distributed suction operating at a greatly improved rate of flow.

Another object resides in accomplishing the foregoing objective by baffle means of novel construction capable of being cast or forged integrally with the base of the buck.

Still another object is to provide baffle means as aforesaid having apertures to avoid trapping of condensate.

A further object is to provide improved circulation of air and vapor from the garment or other article to the inlet of the source of vacuum.

Another object lies in means and a method of introducing ambient air into the buck through unrestricted openings whereby circulation through the buck is considerably enhanced and drying of the article accelerated accordingly.

Other objects and advantages of the invention will become apparent from the ensuing description which, taken with the accompanying drawing, discloses a preferred mode of carrying the invention into practice.

In these drawings:

FIG. 1 is a perspective view of a pressing machine to which the principles of the invention are adapted;

FIG. 2 is a top plan view of the lower buck with the upper plate or cover thereof, in large part, broken away;

FIG. 3 is a cross section taken along the line 3—3 of FIG. 2, but with the grid plate removed;

FIG. 4 is a cross section on the line 4—4 of FIG. 2; and

FIG. 5 is a somewhat enlarged view of a portion of FIG. 4 for a better showing of details.

Where, in the description and claims, reference is made to a buck or lower buck the same is intended to comprehend the bed or table upon which the garment or other article to be pressed rests during pressing irrespective of the means by which pressure is applied to the article. It is also contemplated that vacuum may be applied from above the article as well as from below, although the latter is the accepted convention. In the exemplificative machine, the article to be pressed is deposited on the lower buck and the upper, heated buck brought down thereupon. Any heating medium may be utilized viz., electricity, steam or gas although the first two are those

2

most frequently employed. Moreover, while the working faces of the bucks are shown complementarily convex and concave, these may be flat. The means by which the upper buck is pivoted and the mechanism for raising and lowering the upper buck form no part of the invention per se. In fact, the upper buck may be stationary and the lower buck raised thereagainst.

Broadly regarded, the invention comprises a hollow buck subdivided interiorly by ribs into a plurality of communicating chambers, all of these chambers being in communication with the entire working area of the buck through a grid plate used with or without an overlying yieldable pressing pad. Distributed at strategic positions otherwise than on the working surface are one or more ports through which ambient air may be drawn when the suction is applied. The arrangement and size of these ports is such that the incoming air, sometimes referred to herein as "bleed air," is caused to travel through the several chambers to the opening to which the source of suction is connected, whereby to increase the velocity of the vapor and/or water toward the exhaust fan or other vacuum-applying instrumentality. Stated otherwise, the chambers act as ducts having a somewhat restricted cross section whereby the velocity of the moving mass of intermingled vapor and air is greatly increased. Intercommunication between the several chambers is preferably obtained by providing notches or other apertures in the walls intermediate the same. These walls may also be so arranged as to act as interior support for the grid plate, provided the same is not self-sustaining. To avoid accumulation of water on the floor of the chambers weep holes are provided in the ribs.

Turning now to the drawings, there is shown (FIG. 1) a pressing machine having a base 10, an upper, pivoted, electrically-heated buck 11 and a fixed lower buck 12 carried on a hollow pedestal 13 upstanding from the base. Thus, the pedestal may also serve as a conduit through which vapor and/or water is exhausted from the interior of the buck. For proper mechanical balance and to distribute the force of suction symmetrically, the axis of the pedestal is desirably positioned on the longitudinal, vertical, mid-plane of the buck. The means for providing suction may be of any suitable type. By way of example there is shown a vaned rotor 21 (FIGS. 2 and 4) on the shaft of an electrical motor 22 which latter, as will be understood, rotates continuously while the machine is in use. Communication with the interior of the buck 12 is through the opening or port 24 defined by the upper end of the pedestal 13 and exhaust is via a side outlet 26 which leads, through a hose or other tube, to the exterior of the premises or to a suitable container for receiving water.

The buck 12 comprises a bottom wall 31, front and rear walls 32—32, end walls 33—33, and a cover plate 35. In the example, the parts 31, 32 and 33 are cast integrally with the pedestal and base 10 although any equivalent construction is within the purview of the invention. The cover plate 35, in the form of an arcuate, perforate sheet having the rigidity suitable to its function, is seated in a peripheral recess 37 along the walls 32 and 33 (FIG. 5) and is secured by screws 41 to a central rib 42 to be detailed subsequently. The perforations 44 in the plate 35 have a well-known function, namely to permit water vapor and droplets, i. e. condensate, to be drawn from the article undergoing pressing. In correspondence with the nomenclature of this art, the cover plate 35 is sometimes referred to herein as the grid plate. In practice, a yieldable pad 47 of fabric or other construction overlies the grid plate 35 in order to provide a cushion for the articles pressed thereon. Such pad has interstices of a character permitting passage of suction force and consequent removal of moisture.

The space defined between the walls 31, 32, 33 and the grid plate 35 is subdivided into a plurality of chambers 51 by means of ribs 52, the central one of which is interrupted in the region of the suction opening 24, and the next adjacent pair are arcuate at the same region. 5 As will be apparent, the several chambers 51 are in communication with the openings 44 in the grip plate. Communication between the outermost pairs of chambers and the opening 25 is obtained by notching the outermost pairs of ribs 52 at desirable intervals, for example, as indicated at 53, these notches being in staggered relation, as is clear from FIG. 2, in order to avoid short circuiting of the force of suction. It will also be noted (FIG. 5) that the upper edge of the several ribs 52 is curved congruently with the grid plate 35 to provide support therefore at the interruptions 57 between the notches 55. Although the central rib is shown as uninterrupted for improved support of the grid plate, this rib may also be interrupted in the same manner as the remaining ribs.

From the foregoing, it will have become evident that the force of suction at the opening 24 is distributed substantially uniformly over the entire area of the grid plate with consequent subjection of the entire article being pressed to the vacuum.

To avoid accumulation of condensate on the floor of the chambers 51, weep holes 61 are provided at convenient intervals.

In accordance with the invention, withdrawal of moisture from the article being pressed and from the pad 47 is accelerated by admitting ambient air to the interior of the buck 12. To this end apertures 63 are provided through the buck, preferably the bottom wall 31 thereof, and preferably adjacent the end walls 33-33 whereby atmospheric air is drawn into the buck and serves to induce a current of comparatively high velocity between these apertures and the suction fan. As a result, the vapor and condensate are swept along, so to speak, and delivered to the opening 24 at a considerably higher rate than would be the case in the absence of the apertures 63. In the foregoing connection, it will be comprehended that the interstices of the fabric cover 47 tend to throttle flow of vapor and condensate withdrawn from the garment with consequent retardation in the rate of moisture extraction, and that this condition is largely overcome by the swiftly moving mass of bleed air. If desired, the openings 63 may be in the end walls 33 or side walls 32 as long as they are sufficiently remote from the opening 24 to obtain the beneficial result above described.

From the foregoing it will have become evident that the invention results in a high degree of performance since the moisture is extracted from the garments, etc. at a rate far greater than has been the case with other vacuum systems presently available.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

I claim:

1. In a fabric press provided with suction means, a buck comprising an essentially hollow body having its interior space defined by a bottom wall, lateral walls and a perforate top wall to support the article operated upon, a port in said body adapted to be connected to said suction means to reduce the air pressure in said space below atmosphere whereby to extract moisture from the article, said bottom wall having a plurality of unrestricted openings in communication with ambient atmosphere whereby said reduction in air pressure induces flow of atmospheric air into said space and toward said suction means to increase the rate of extraction of moisture and its exhaust from said space.

2. In a fabric press provided with suction means a buck

comprising a hollow body having a perforate wall providing a surface to support the article operated upon, said body having a port adapted to be connected to said suction means to extract moisture from the article, said body being provided elsewhere than in said perforate wall with an unrestricted opening to ambient atmosphere to admit air into said body under suction for exhaust with moisture extracted from the article.

3. In a fabric press provided with suction means, a buck comprising an elongated, parallelepipedic, essentially hollow body having its interior space defined by a bottom wall, front and rear walls, end walls and a perforate top wall to support the article operated upon, a port in said body adapted to be connected to said suction means to reduce the air pressure in said space below atmosphere whereby to extract moisture from the article, a plurality of longitudinal partitions extending between said end walls and top and bottom walls subdividing said space into a plurality of chambers extending from one end wall to the other, the perforations in the top wall being distributed coextensively with said chambers to provide suction through all of said perforations, said partitions having staggered apertures providing communication between said chambers, and means providing fluid communication between said port and at least one of said intercommunicating chambers.

4. The combination in accordance with claim 3 further characterized by the provision in said bottom wall of a plurality of unrestricted openings in communication with ambient atmosphere to admit atmospheric air into said chambers for joint flow with said moisture.

5. In a fabric press provided with suction means, a buck comprising an essentially hollow body having a perforate top wall to support the article being operated upon, an opposite bottom wall having a support for the body, a front wall, a rear wall and a pair of opposite end walls, said front and rear walls being substantially longer than said end walls, said walls together defining the space within the body, a conduit extending from said body adapted to be connected to said suction means to draw off moisture from the article, said conduit lying in the longitudinal, medial, vertical plane of the body, a partition extending between said top wall and bottom wall in said plane and interrupted at said conduit, other partitions flanking both sides of said first partition extending between said top wall and bottom wall and between said end walls, said first partition and other partitions together with the body-defining walls defining a plurality of chambers within said body, said other partitions being interrupted in staggered fashion to provide fluid communication between the several chambers and said port.

6. In a fabric press provided with suction means, a buck comprising an elongated, substantially parallelepipedic, essentially hollow body having its interior space defined by a bottom wall, lateral walls and a perforate top wall to support the article operated upon, a port in said body adapted to be connected to said suction means to reduce the air pressure in said space below atmosphere whereby to extract moisture from the article, a plurality of partitions extending between ones of the lateral walls and top and bottom walls subdividing said space into a plurality of chambers, said partitions having staggered apertures providing tortuous paths of communication between said chambers, the perforations in the top wall being distributed coextensively with said chambers to provide suction through all of said perforations, and passage means providing fluid communication between said port and at least one of said intercommunicating chambers.
